UNITED STATES PATENT OFFICE.

JAMES W. ASHBAUGH, OF BREMEN, OHIO.

COMBINATION GAS-VALVE.

1,171,691.

Specification of Letters Patent. Patented Feb. 15, 1916.

Application filed June 1, 1915. Serial No. 31,429.

To all whom it may concern:

Be it known that I, JAMES W. ASHBAUGH, a citizen of the United States, residing at Bremen, in the county of Fairfield and State of Ohio, have invented certain new and useful Improvements in Combination Gas-Valves, of which the following is a specification.

This invention relates to combination gas valves and is designed generally as an improvement in combination valves wherein the gas and air leading to any type of ordinary burner structure are regulated.

The present invention is designed particularly as an improvement over my previous patents shown and described in Patent Nos. 852,591 and 1,093,026, issued on May 7, 1907, and April 14, 1914, respectively.

The main object of my invention resides in the provision of a structure wherein the orificial outlet for the gas is decreased in size as the structure controlling the admission of gas to the valve structure as a whole, is decreased, the size of the orificial outlet of this gas from the valve structure is also proportionately reduced in size. This arrangement is resorted to to maintain the velocity of outflow approximately constant for all practical limits between wide open and closed positions of the structure governing the inlet of gas. I find it desirable to maintain approximately the same rate of flow of gas out of the valve structure as a whole, in order that it may properly mix with the required amount of air as it passes through the mixer structure. In this connection, my preferred arrangement is such that the regulation of the size of the orificial outlet is rendered automatic by the turning on or off of the ordinary valve structure for controlling the admission of gas.

A further object of my invention resides in the combination of gas admission structure, together with the outlet control with a supplemental air regulating structure of the nature so that the amount of air permitted to enter the mixture structure as a whole, is reduced or increased as the volume of gas passing therethrough is reduced or increased respectively.

A further object of my invention resides in the provision of a peculiarly novel type of nozzle element whereby the flow of gas from the structure as a whole, may be regulated by increasing or decreasing the size of its outlet.

The preferred embodiment of my invention is shown in the accompanying sheet of drawings, in which similar characters of reference designate corresponding parts, 60 and in which:

Figure 1 is a view in elevation, partially in section, showing my improved valve structure, Fig. 2 is a vertical section of the structure shown in Fig. 1, Fig. 3 is a transverse section taken on line 3—3 of Fig. 2 and looking in the direction of the arrows, Figs. 4 and 5 are side elevations and plan views respectively of the nozzle element used by me, Fig. 6 is a view looking into the 65 face of the valve structure and showing the regulator shutter partially closed and also showing the nozzle element closed to decrease the size of the gas outlet, and, Fig. 7 is a view showing the shutter structure 70 at its greatest opening and also showing the gas outlet at its greatest opening.

In the drawings, there is shown a valve casing 1, this valve casing being of tubular construction and having a tapered inner bore. One side of this valve casing is provided with a type of fitting shown at 2, this fitting being threaded as at 3, to receive the gas supply pipe, the fitting tube itself forming the gas intake portion. Within this 80 casing there is rotatably mounted a correspondingly tapered valve plug 4, this plug being of a hollow structure such as is shown at 5 and being further provided with a transverse slot 6 of a length so that the 85 valve plug may be turned through an arc of approximately 180 degrees between closed and open positions of the valve. This slot is so positioned with respect to the gas inlet portion that in its normally open position, it is in communication with the reduced 90 passage 7 formed in this gas inlet portion and by means of these passages the gas is permitted to enter the hollow space 5.

Within this hollow space there is confined a nozzle element designated generally by the numeral 8, this nozzle element being provided with a plurality of longitudinally extending slits 9 at its outlet end, this outlet end being further rounded or reduced in size as is shown at 10. The opposite end of this nozzle member is provided with an inclined face or cam formation 11 designed to coöperate with an actuating screw or pin 12 carried by the casing. This end of the 105 nozzle is further provided with a slot 13 designed to coöperate with a pin 14 carried

by the valve plug 4 in order that there shall not be a relative movement between the nozzle element and the plug during the normal operation of the device. The rounded end 5 10 of the nozzle 8 co-operates with an outlet fitting 15 adjustably held in the forward end of the valve plug 4 by means of the threaded connection shown at 16, the interior of the fitting 15 being correspondingly rounded as is indicated in order that the prongs formed by the slits 9 may be wedged toward each other to reduce the size of the outlet.

The forward end of the valve plug 4 also 15 rigidly carries an air shutter 17, this shutter being in rigid engagement with the plug by means of the flange fitting shown at 18, this fitting coming into wedging engagement with one face of the shutter by means of the 20 threaded connection 19, thus forcing it into wedging engagement with the shoulder 20 on the end of the valve plug. This shutter co-operates with the bell member designated 25 21, in that it plays over its straight end 22, this end being provided with a semi-circular opening 23. The opposite end of the plug 4 is provided with an operating handle designated 24, the collar member 25 forming a portion of the handle structure and being 30 held in position on this plug by means of the washer 26 and the screw 27. The washer 28 and the threaded collar 29 are also provided to maintain the plug in its true position with respect to the casing during the normal 35 operation of the valve as a whole.

The operation of my device is as follows: Assuming the parts to be in the positions indicated in Figs. 1, 2, 3 and 6, it will be noted that the nozzle member has been 40 forced forwardly so that the prongs formed by the slits 9 have been forced toward each other to reduce the size of the gas outlet and this reduction is made so that the gas will issue in solid cylinder form. This reduction 45 in size is effected by the engagement of the screw or pin 12 with the cam face 11 on the end of the nozzle member, thus forcing it forwardly into wedging engagement with the outlet fitting 15. Movement of the handle 24 downwardly as indicated in Fig. 7 will turn the valve plug 4 so that the passage 7 in the inlet formation 2 will be entirely uncovered, thus permitting the maximum amount of gas to enter the plug. At 50 the same time, the pin 12 has been so moved that the nozzle 8 may move rearwardly a slight distance to enable the prongs to expand to thereby increase the size of the orificial opening. This rearward movement is 55 effected by the resiliency of the prongs 6 in their co-operation with the tapered inside wall of the outlet fitting 15. During this operation, the shutter 17 has been moved from the position indicated in Fig. 6 to the 60 position indicated in Fig. 7 thus uncovering

practically all of the slotted opening 23 in the bell 21 and thereby permitting the entrance of the maximum amount of mixing air. Thus it will be apparent that the velocity of flow of gas from the valve structure is approximately constant, the size of the orificial outlet being considerably reduced where the supply is decreased. This decrease in supply naturally decreases the pressure of the gas within the fitting as a 70 whole and consequently the reduction in size of its outlet opening will cause the gas to pass forwardly in a reduced stream approximately at the same velocity as the larger stream under a greater pressure when the valve is completely open. Also, the amount of air supplied to effect the combustible mixture is similarly regulated and both of these regulations take place automatically by turning of the handle 24 one way or the 75 other.

What I claim, is:

1. A combined air and gas controlling valve comprising a valve casing having a gas inlet portion, a valve plug within said casing arranged to decrease the supply of gas by a turning movement, and means for decreasing the size of the orificial outlet for said gas and for emitting it in solid cylinder form as its supply is decreased. 90

2. A combined air and gas controlling valve comprising a valve casing having a gas inlet portion, a hollow valve plug within said casing arranged to communicate with said inlet in a manner to decrease the supply of gas by a turning movement, and means within said hollow plug operable upon such turning movement to decrease the size of the orificial outlet. 100

3. A combined air and gas controlling valve comprising a valve having a gas inlet portion, a valve plug within said casing arranged to decrease the supply of gas by a turning movement, an air mixer structure including a movable shutter, means for moving said shutter to decrease the air supply, and means for decreasing the size of the orificial outlet for the gas and for emitting it in solid cylinder form, said two last named means being operated by the turning of said plug. 105

4. A combined air and gas controlling valve comprising a valve casing having a gas inlet portion, a hollow valve plug within said casing arranged to communicate with said inlet in a manner to decrease the supply of gas by a turning movement, a nozzle within said plug, said nozzle having a plurality of longitudinally extending slits beginning at the outlet end, and means whereby the slotted end of said nozzle is squeezed together by a turning movement of said plug to decrease the gas supply and at the same time decrease the size of the orificial outlet. 125

5. A combined air and gas controlling 130

valve comprising a valve casing having a gas inlet portion, a hollow valve plug within said casing arranged to communicate with said inlet in a manner to decrease the supply of gas by a turning movement, a nozzle within said plug, said nozzle having a plurality of longitudinally extending slits beginning at the outlet end, said nozzle carrying a cam formation at its rear end, connecting means between said nozzle and said plug preventing their relative rotation, and a pin

carried by said casing engaging said cam formation to wedge the slotted end of said nozzle together to decrease the size of the orificial outlet when said plug is turned to 15 decrease the supply of gas.

In testimony whereof I affix my signature in presence of two witnesses.

JAMES W. ASHBAUGH.
